ATTORNEY

UNITED STATES PATENT OFFICE.

EDWARD JAMES HOLLAND, OF PRESCOTT, ONTARIO, CANADA.

DESIGN FOR A COMBINATION LAMP AND GONG.

54,260.

Specification for Design.

Patented Dec. 9, 1919.

Application filed July 25, 1919. Serial No. 313,391. Term of patent 3½ years.

To all whom it may concern:

Be it known that I, EDWARD JAMES HOLLAND, a subject of the King of Great Britain, residing at Prescott, in the Province of Ontario, Canada, have invented a new, original, and ornamental Design for a Combination Lamp and Gong, of which the following is a specification, reference being had to the accompanying drawing, forming a part thereof, and in which—

Figure 1 is a side elevation, and

Fig. 2 a top end view of a combination lamp and gong embodying my design.

I claim:

The ornamental design for a combination lamp and gong, as shown.

EDWARD JAMES HOLLAND.
